FACING TAPE FOR VENETIAN BLINDS

Ralph H. White and Donald J. McNevin, Chicago, Ill.

Application April 5, 1937, Serial No. 135,098

8 Claims. (Cl. 156—17)

Venetian blinds have now been developed to a state where they are very satisfactory but there is still one very annoying feature in connection with them. This is the soiling of the ladder 5 tapes which support the slats in properly spaced relationship and tilt the slats. It is of course very difficult, if not impossible, to clean the tapes satisfactorily on the blind, and to remove and replace them practically amounts to rebuilding 10 the blind.

The difficulty of replacing the tape has also been a handicap in the event of redecorating the rooms in which the blinds are located since a tape of a color chosen to go with one color scheme 15 often will not be satisfactory with a different color scheme.

The main object of the present invention is to overcome the above mentioned difficulties. This is done by providing a facing tape which 20 may easily be secured to the original ladder tape to conceal the same and give the appearance of an entirely new ladder tape.

Further objects and advantages of the invention will appear as the description is read in connection with the accompanying drawing, in 25 which:

Fig. 1 is a face view of a Venetian blind embodying one form of facing tape of the present invention, one tape being partially broken away 30 to show the original ladder tape therebelow.

Fig. 2 is a fragmentary vertical sectional view showing the application of the facing tape to the ladder tape.

Fig. 3 is a fragmentary front view corresponding to Fig. 2.

Fig. 4 is a horizontal sectional view taken on the line 4—4 of Fig. 2.

Fig. 5 is a fragmentary perspective view showing one form of attachment of the fastener clip 40 to the facing tape, and

Fig. 6 is a similar view showing modifications in the clip and its manner of attachment.

Although this invention may take numerous forms, only two have been chosen for illustration. These have been illustrated in connection with a Venetian blind formed mainly of slots 11 supported by conventional ladder tapes 12. As is well known, the ladder tapes 12 are secured at their tops to some manipulating structure such as a tilt bar 13 which may be tilted in either direction by the tilting cord 14. The ladder tapes include cross tapes 15 which give the ladder tape its name and on which the slats rest, these cross tapes being woven into or sewn to the vertical tapes of the ladder tapes at positions spaced

according to the spacing of the slats desired. The lower ends of the ladder tapes 12 are secured to a bottom bar 16. Some means for raising and lowering the slats is usually provided, and in the illustrated form this comprises a raising rope 17 secured to the bottom rail 16 and extending upwardly through the blind in a position concealed by each ladder tape and over pulleys 18 to a position of convenient access near one side of the window frame 19 in which the 10 blind is positioned.

Venetian blinds are expected to last for years and will do so, but in the course of a year or two the ladder tapes 12 are likely to become very dirty and unsightly in appearance. Although 15 the slats 11 may be cleaned with relative ease, the ladder tapes 12 cannot be cleaned satisfactorily on the blind and it is evident that their removal amounts to almost complete disassembly of the blind. According to the present invention a facing tape 20 is provided which may be sold by the yard and which may readily be applied over the original ladder tape to conceal the same and present as satisfactory an appearance as if a new ladder tape were provided. Such a 20 facing tape is preferably slightly wider than the original ladder tape, as seen best in Figs. 3 and 4. Since the conventional ladder tapes are 1½ inches wide, the facing tapes may be 1½ inches wide.

Almost any type of securing means may be used for securing the facing tape 20 to the ladder tape or directly to the slats of the blind if preferred, but in either case the securing means should be concealed and should be of a form 35 which will not unduly injure the ladder tape or the slat. In the illustrated form clips 21 are used which may be either permanently or detachably secured to the facing tape 20 at regular intervals and include finger portions 22 40 designed to hook around the sides of the ladder tape 12 and engage it with sufficient firmness to hold the facing tape in place. It will be evident that the hook-like fingers 22 may be substantially rigid and of the shape shown or they 45 may be of a more resilient nature, in which case they should tend to press against the body portion of the clip 21. Likewise, the fingers 22 could be in the form of prongs of a softer metal to be doubled over by hand in application of the 50 facing strip 20 to the ladder tape 12. Fig. 6 illustrates a flat ribbon 21' having finger portions 24 which can be bent over at the position of the dotted lines to clamp around the edges of the ladder tape. Of course, instead of hooking 55

around the edges of the ladder tape 12 the fingers 22 or 24 could pierce the ladder tape if preferred. The illustrated form of clip is preferred because it is not only easily attached to 5 the ladder tape but is easily removed when it is desired to replace the first facing tape with a new facing tape. Although a wire clip has been used, it could be formed of a flat ribbon with the same advantages.

10 The clips 21 may be secured to the facing tape 20 in any unobtrusive manner. According to the embodiment illustrated in Figs. 4 and 5 loops 23 are provided, which may be formed by a pair of extra cords or heavy threads 25 through which 15 the clip 21 extends. Such a cord or heavy thread may extend longitudinally of the facing tape 20 as seen in Fig. 5, being mainly on the back side thereof so as to be unobtrusive. The small loops 26 which extend to the front of the tape are preferably so positioned as to blend with the ornamental design 27. The loops 23 are preferably long enough to permit the clips 21 to be inserted therein at will and removed easily to facilitate cleaning the facing tape 12. The loops 28 are 20 of a self-locking nature to prevent the cord or thread 25 from being pulled out. Of course, entirely independent stitches could be used for each clip 21 if preferred.

Instead of the thread or cord loops, tape loops 30 may be provided by stitching a wide band or two widely separated relatively narrow bands of tape on the back side of the facing tape, the stitches of course being omitted at the position of the loop. The clips 21 may be passed through the 35 various securing loops after these loops are completed or the loops may be woven or stitched in the facing tape 20 around the clip 21 properly placed on the facing tape 20. This has been illustrated in Fig. 6 in which the loops 28 may 40 comprise the back portions of the thread of which the design 27 is formed.

Although it is desirable that the tape be such that it may satisfactorily be sold by the yard and cut to fit particular blinds, the appearance of a 45 finished or hemmed end may be attained simply by folding over the end portion 27' of the cut tape and extending it through the nearest clip 21 before the facing tape is applied to the ladder tape. In the case of the upper end of the fac- 50 ing tape the doubled over end portion 27 may be left upstanding to partially conceal the raising cord 17 and the securing tacks at the upper end of ladder tape 12, thus presenting a neater appearance than did the original ladder tape. 55 Likewise, the lower end of the facing tape 20 may present a neater appearance than the original ladder tape by being extended entirely around under the bottom rail 16, thus concealing the ends of the original ladder tape. In this event the fac- 60 ing tape 20 will be hooked to the far side of the ladder tape 12 approximately adjacent the bottom rail 16 as shown in Fig. 2, its end being folded in as in the case of the upper end portion 27.

65 From the foregoing it is seen that a facing tape is provided which is so readily applied to the ladder tape of conventional blinds that there is no longer any need to have dirty ladder tapes exposed or to change the ladder tape when the color scheme of the room in which the Venetian blind is located is changed.

The disclosures of this application are illustrative and the invention is not to be limited by them. In fact, if modifications or improvements are not at once obvious, they may be de-

vised in the course of time to make additional use of the broad ideas taught and covered by this application. The claims are intended to point out novel features and not to limit the invention except as may be required by prior art.

We claim:

1. In combination with the ladder tape of a Venetian blind, a facing tape having a width at least as great as the width of the ladder tape, a series of loops on the back side of the facing tape, and fastening means secured to the facing tape by the loops and having fingers securing the facing tape to the ladder tape whereby the facing tape completely conceals the ladder tape from normal view.

2. In combination with the ladder tape of a Venetian blind, a facing tape secured thereto by detachable securing means, the facing tape being sufficiently wide to substantially conceal the ladder tape and the securing means from normal view.

3. A facing tape for application to a Venetian blind ladder tape having loops on the back side thereof and fastening means secured to the facing tape by the loops and adapted to secure the facing tape to a ladder tape, the fastening means being substantially invisible from the front of the facing tape.

4. In combination with the ladder tape of a Venetian blind, a facing tape having an ornamental front face and of a width at least as great as the width of the ladder tape and fastening means for readily fastening the facing tape to the ladder tape with ready detachability secured to the facing tape by means blending with the ornamental design thereon so as to be substantially unnoticeable.

5. A facing tape for Venetian blind ladder tapes including an extensive length of tape adapted to have desired lengths of tape cut therefrom and having fastening means secured on its back side at close intervals by loops and adapted to secure the facing tape readily to a ladder tape, the fastening means being adapted to also secure the cut end of the tape in a folded-under position.

6. The combination of a Venetian blind including a tilt rail, a ladder tape secured thereto in exposed position, a plurality of slats supported by the ladder tape, and a facing tape secured to the ladder tape in a readily detachable manner by concealed securing means, the facing tape extending above the tilt rail to conceal the point of attachment of the ladder tape to the tilt rail.

7. A Venetian blind including a head bar, a tilt rail therebelow, tape means secured to the tilt rail, a plurality of slats supported by the tape means, and a raising cord extending from the head structure down through the tilt rail and slats, the tape means extending freely upwardly above the tilt rail to conceal a portion of the raising cord thereabove.

8. A Venetian blind including a plurality of slats, a ladder tape normally supporting the slats in spaced relationship, tilt means for supporting and manipulating the ladder tape, a bottom rail below the slats having the ladder tape secured to the bottom thereof, and a facing tape secured to the ladder tape on one side of the blind substantially concealing the ladder tape and extending under and around to the far side of the bottom rail to conceal the points of securing the ladder tape to the bottom rail.
